DRINKING GLASS

Arne Lundin, Halmstad, Sweden, assignor to
Duni Bila AB, Halmstad, Sweden

Filed Mar. 11, 1974, Ser. No. 450,183

Claims priority, application Sweden Sept. 11, 1973

Term of patent 14 years

Int. Cl. D7—01

U.S. Cl. D7—6

FIG. 1

FIG. 2

FIG. 3.

FIG. 1 is an elevational view of a drinking glass of my new design;

FIG. 2 is a perspective view of the drinking glass of FIG. 1, showing my new design.

FIG. 3 is a bottom plan view of the drinking glass of FIG. 1.

The stippled area of the drinking glass is stippled to indicate that the visible surface is roughened.

The bottom of the drinking glass is plain.

I claim:

The ornamental design for a drinking glass, as shown and described.
